UNITED STATES PATENT OFFICE.

JOHN VAN BRUNT, OF FLUSHING, NEW YORK, ASSIGNOR TO COMBUSTION ENGINEERING CORPORATION, OF NEW YORK, N. Y., A CORPORATION OF NEW YORK.

CHAIN GRATE.

Application filed July 19, 1923. Serial No. 652 514.

My invention relates particularly to furnaces of the type in which the fuel supporting grate comprises an endless belt or chain that extends longitudinally of the fire box of the furnace, the fuel being supported upon the upper run of the chain. In grates of this type it is important that there shall be an adequate supply of air to the fuel supporting surface thereof to support combustion, and to maintain the component parts thereof at sufficiently low temperature to prevent injury thereto and to prevent the formation of clinkers thereon. To provide for this, air spaces or openings are provided between adjacent sides and ends of the links or other fuel supporting members of the grate, air being supplied to the space between the runs of the grate to enable it to pass upwardly through said air spaces or openings in the upper run to the fuel. In the operation of such grates, however, as heretofore constructed, it has been found that fuel and ashes are liable to work or sift downwardly through said spaces or openings in the upper run of the chain, which is objectionable because of the loss of fuel and the difficulty of removing the ashes that drop down into the space between the runs of the grate.

The principal object of the present invention is to overcome the disadvantages above described of the prior constructions while retaining all of the advantages.

The following is a description of my invention, reference being had to the accompanying drawings, in which,—

Figure 1 is a sectional elevation of a portion of a chain grate, the links being shown in elevation and the pivotal connections of the links being shown in section, embodying the features of the invention in their preferred form;

Fig. 2 is a similar view of another portion of the grate showing particularly the links of the grate that are engaged by the sprocket teeth of the driving drum for the grate, a sprocket tooth being shown in section;

Fig. 3 is a plan view of a portion of the upper run of the grate; and

Figs. 4 and 5 are sectional views taken on the lines 4—4 and 5—5 of Figs. 1 and 2, respectively.

The chain grate illustrated in the drawings is provided with rows of links 2 and 4 that are alternately arranged, the links of each row being arranged end to end and the links of

the several rows being arranged in staggered relation with their ends pivotally connected by pivot pins 6 extending through hubs 8 on opposite sides of each link. Certain of the links 2 are provided with recesses or sockets 10 (Figs. 2 and 5) between the hubs thereof for receiving the teeth of the usual sprocket wheel or drum 11 over which the grate passes, the ends of the links 4 arranged between said recessed links 2 being cut away at 12 so as to clear the sprocket teeth. The several links are provided with substantially flat fuel supporting surfaces 14.

In the construction illustrated in the drawings, each of the links 4 is suitably recessed or undercut on opposite sides thereof to form fuel supporting flanges 16 extending from end to end thereof. Each of the links 2 is provided, on opposite sides thereof, with suitable flanges 18 extending longitudinally thereof having their ends curved concentrically with the axes of the pivot pins 6. The flanges 18 are spaced a suitable distance from the fuel supporting surface of the link so that when the links are assembled they extend beneath the flanges 16 of the adjacent links 4; the portions 20 of the flanges 16 that are arranged directly above the curved ends of the flanges 18 being curved concentrically with these curved ends. The top surfaces of the flanges 18 are spaced a slight distance beneath the flanges 16 and the longitudinal edges of these flanges 18 are spaced a slight distance from the adjacent portions of the links 4. The flanges 16 are each provided with a plurality of vertical channels 22. The forward end of each of the links of each row is provided with a forward projection or tongue 24 having its top surface forming a continuation of the fuel supporting surface of the links and each projection 24 extends into a transverse recess 26 in the rear end of the next succeeding link. The adjacent ends of the links are spaced a slight distance apart and the projections 24 are spaced a slight distance from both the vertical and horizontal walls of the recesses 26.

With this construction it will be apparent that a free air supply is provided to the fuel supporting surface of the grate through the spaces between the superposed flanges 16 and 18, the channels 22, and the spaces between the projections 24 and the walls of the recesses 26; and that the superposed flanges 16 and 18 will effectively prevent the sifting of

fine particles of fuel and ashes between the sides of adjacent links, and the projections 24 will effectively prevent the sifting of fuel and ashes downwardly between adjacent ends 5 of the links. The curved ends of the flanges 18 and the curved lower surfaces 20 of the flanges 16 enable the relationship of these flanges to be maintained while their links are passing over the supporting and driving 10 drums or sprocket wheels of the grate.

At various points on the surfaces of the links slanting recesses 27 are provided so as to retain ashes from the burning fuel. These recesses extend only partly across the links 15 and have their open ends removed from the channels 22 so as not to discharge therein.

As will be evident to those skilled in the art my invention permits of various modifications without departing from the spirit there- 20 of or the scope of the appended claims.

What I claim is:

1. A chain grate comprising a plurality of rows of links, the links of each row being arranged end to end, the links of the several 25 rows being arranged side by side in staggered relation with their ends pivotally connected, and adjacent links of adjacent rows having one a flange extending longitudinally thereof and the other a recess for receiving the 30 flange, each flange extending substantially the length of the link and spaced a distance below the fuel supporting surface of the link throughout its length, and each link of alternate rows having one such flange on each 35 side thereof, and each link of the other rows having one such recess on each side thereof.

2. A chain grate comprising a plurality of rows of links, the links of each row being arranged end to end, the links of the several 40 rows being arranged side by side in staggered relation with their ends pivotally connected, and adjacent links of adjacent rows having one flange extending longitudinally thereof and the other a recess for receiving the flange, 45 the flange being spaced from the wall of the recess so as to enable air to pass upwardly between the flange and said wall, each of the links of alternate rows having one such flange on each side thereof and each of the 50 links of the other rows having one such recess on each side thereof.

3. A chain grate comprising a plurality of rows of links, the links of each row being arranged end to end, the links of the several rows being arranged side by side in staggered 55 relation, and adjacent links of adjacent rows having one a flange extending longitudinally thereof with both ends of the flange curved about the axes of its pivotal connections, respectively, the two adjacent links having recesses for correspondingly receiving the 60 curved ends of said flange, respectively, each of the links of alternate rows having one such flange on each side thereof, and each of the links of the other rows having one such 65 recess on each side thereof.

4. A chain grate comprising a plurality of rows of links, the links of each row being arranged end to end and the links of the several rows being arranged side by side in staggered 70 relation, adjacent links of adjacent rows having one a flange extending longitudinally thereof with the ends of the flange curved about the axes of its pivotal connections respectively, and the other having a recess for 75 receiving the flange, with the flange spaced from the wall of the recess so as to enable air to pass upwardly between them, and each of the links of alternate rows having one such flange on each side thereof, and each of the 80 links of the other rows having one such recess on each side thereof.

5. A chain grate comprising a plurality of rows of links, the links of each row being arranged end to end, the links of the several 85 rows being arranged side by side in staggered relation with their ends pivotally connected and the links of adjacent rows being provided with cooperating flanges extending longitudinally thereof and arranged in super- 90 posed relation and spaced apart, each of the upper flanges extending substantially the length of the link and having a series of vertical channels leading from said space between the flanges to the fuel supporting surfaces of the links, each of the links of alternate rows having one such flange on each side thereof and each of the links of the other rows having one such recess in each side 95 thereof.

JOHN VAN BRUNT.
